UNITED STATES PATENT OFFICE.

HERMANN GÄRTNER, OF LINTORF, NEAR DUSSELDORF, GERMANY.

WIRE-NAIL MACHINE.

1,098,244.

Specification of Letters Patent. Patented May 26, 1914.

Application filed December 23, 1912. Serial No. 738,240.

To all whom it may concern:

Be it known that I, HERMANN GÄRTNER, a citizen of the German Empire, residing in Lintorf, near Dusseldorf, in said Empire, have invented certain new and useful Improvements in Wire-Nail Machines, of which the following is a specification.

The present invention relates to a machine for the manufacture of wire nails and tacks with a clamping device located in alinement with the moving wire in front of the knife box and serving as head forming lower dies.

The novelty of the invention resides in the fact that the one-half head forming lower dies rests on the knife box and one half of the knife box and the opposite half of the head forming lower dies are fixed upon the movable half of the knife box, whereby only two operating levers are necessary and owing to this arrangement both ordinary wire pins and also nails with long tapering shanks such as tacks, roofing nails and the like can be manufactured on this machine. Notwithstanding this arrangement of the tools, nails and tacks of different length may be manufactured, and to accomplish this the feed movement of the wire is obtained in two strokes by means of a cam plate with one fixed and one radially displaceable nose or protuberance, and the length of one of the strokes may be modified by adjusting the displaceable nose. In order to obtain the necessary quick return movement of the head forming die, the head is moved by the coöperation of a cam plate and a spring. Accordingly, if the spring should break, the cam plate will prevent the head die from remaining in its pressing position and impeding the operation of the machine.

A constructional form of the machine embodying the invention is illustrated by way of example in the accompanying drawing, in which:—

45 Figure 1 is a longitudinal section thereof. Fig. 2 is a plan view of Fig. 1. Fig. 3 is a rear elevation of Fig. 1. Fig. 4 is an elevation in larger scale of the combined knife and jaw box; Fig. 5 a section along A—A of Fig. 4; Fig. 6 a section along B—B of Fig. 50 Figs. 7 and 8 illustrate details of the knife box. Figs. 9 and 10 diagrammatically illustrate the present improved arrangement in two different positions.

55 As shown in the drawing, the knife box a , made in two parts a^1 , a^2 , is provided with

four knives b , and a plate c inserted in the knife box in front of the knives, which plate holds the tools b and this plate is secured in such a manner by screws 10 and 2, 60 that the movement of one half of the knife box relatively to the other is assured. To render this possible, oblong slots 3 for screws 2 are provided in the knife box half a^1 and round holes for screws 10 provided in the knife box half a^2 , making the former movable and the latter stationary. The plate c is U-shaped, leaving a dove-tail guide d between its shanks for receiving the head-forming jaws e , f , which coöperate with the head die g to shape the nail head. Each one of the knives b may be moved in the usual manner in the respective box halves by means of their set screws, whereas only one f of the jaws e , f , moves during operation in the plate c . The movable box half a^1 , together with its knives b and the jaw e are under the influence of a spring 4, Fig. 2. The jaw e is firmly supported by the set screw h , while the jaw f supported in the guide slot d of the plate c , is subjected to the action of a lever i through a set screw 5, which lever is operated in the known manner by means of a cam plate 7 against which the lever is constantly pressed by a 75 spring 6. The displacement of one half a^1 of the box and of the cutters therein is produced in a similar manner by a lever k arranged on the other side of the machine and operated from the driving shaft, by the intermediary of a cam plate 8.

In the present invention as illustrated in Figs. 9 and 10, one jaw e^9 is fixed and the knife b^8 is movable, while the counter jaw f^9 is movable and the knife b^9 fixed. Precisely in the same manner as the knife b^9 , the innermost edge of the head of the counter jaw e^9 is located in the axis of the wire supplied, so that with the tool open, the wire is guided during its feed by the counter 95 jaw e^9 and the knife b^9 ; that is to say it is guided centrally thereby enabling the head to be correctly formed. When this has been effected, the movable counter jaw f^9 moves back, so that the loose knife b^8 in the succeeding pressing of the point can depress the shank of the nail to such an extent that the point of the nail becomes perfectly central.

Beneath the head die g which is located 110 in front of the knife box a , and the jaw e and normally drawn back by the spring k^1 ,

is situated another cam plate m , which by means of a protuberance m^1 , after a given rotation, acts upon one arm of a bell crank lever n , the other arm of which engages the head die by means of a ball joint and pushes the head die g forward, against the action of the spring k^1 , for the purpose of pressing the head. During the continued rotation, the protuberance m^1 enters the recess 7
 10 suitably provided in the head die g and directly returns the latter to its original position, if this has not already been effected by the spring k^1 . The cam plate m^2 is provided with a protuberance m^2 which acts in 15 the usual manner upon the lever o^1 depressed by the spring o , whereby the lever o^2 , which reaches as far as the counter jaws, throws down the still adhering nail.
 The holder p of the rocker p^1 , serving for 20 feeding the wire, is connected by a tension rod q with the crank pin r adjustable to different radii of a conveyer lever r^1 rotatably mounted on the frame of the machine close to the driving shaft. On its lower part this 25 conveyer lever r^1 carries a roll s , the periphery of which is slightly off-set from it. Protuberances t , t^1 of the cam plate u , mounted on the driving shaft, actuate the roll s during their rotation in such a manner that the 30 conveyer lever r^1 performs a rocking movement and thus feeds the wire. The conveyer lever r^1 bears upon a stop v in such a manner that the circular portion of the cam plate u does not come into contact with it 35 but only the protuberances t , t^1 . If the cam plate u comprises a plurality of protuberances, which may of course be of different sizes, the screw of the stop v can be adjusted in such a manner that the guide roll s 40 is only touched by the desired protuberances t^1 which obviously must always be higher than the other fixed protuberances. The protuberance t is displaceably arranged in a radial slot w in the cam plate u and by means 45 of a set screw x and of a scale y provided on the slot w it can be shifted more or less outside the periphery of the disk u in order to obtain a complete stroke of any desired length and nails of corresponding size.
 When the fixed protuberance t^1 presses 50 back the conveyer lever r^1 , the cutter p^1 produces the first wire feed, which can be regulated by the adjustable crank stud r in such a manner that after completing this partial 55 feed movement, the wire protrudes from the plate c and its jaws e , f , only to an extent necessary to provide material enough for the formation of the head. After the completion of the first feed movement the 60 lever i presses the wire between the counter jaws e , f , of the plate c and the head forming die g is brought against it and forms the head. When the head forming die g springs back and the lever i effects its return movement the conveyer lever r^1 is struck by the 65

protuberance t , thereby causing it to rise again, whereby the wire is fed forward the second time a distance corresponding to the desired length of a nail. The point of the nail is thereupon formed by the lever k and the knife b in the knife box a . As soon as the nail is finished, pressed and the first feed movement of the next nail occurs, the finished nail which still adheres to the wire is separated from it by the action of the levers o^1 and o^2 . The lever o^2 is thereupon returned to its normal position by the spring o .
 I claim:

1. A machine for making wire nails and pins, having a stationary knife carrier and 80 a slidable knife carrier, knives in each of the carriers radiating from the axis of the wire, a frame situated in front of both and having positive connection with the stationary carrier, a pair of head forming dies 85 in said frame, one of said dies being slidable and the other stationary in said frame during operation; and means for reciprocating said movable die and said slidable carrier.

2. A machine for making wire nails and 90 pins, having a stationary knife carrier and a slidable knife carrier, knives in each of the carriers radiating from the axis of the wire, a frame situated in front of both and having positive connection with the stationary carrier, a pair of head forming dies 95 in said frame, one of said dies being slidable and the other stationary in said frame during operation; a lever engaging with said movable die, a cam actuating said lever and 100 a spring pressing said lever against said cam.

3. A machine for making wire nails and pins, having a stationary knife carrier and a 105 slidable knife carrier, knives in each of the carriers radiating from the axis of the wire, a frame situated in front of both and having positive connection with the stationary carrier, a pair of head forming dies in said frame, one of said dies being slidable and 110 the other stationary in said frame during operation; a spring engaging with said slid- 115 able carrier and tending to draw the carrier outward from the wire, a lever impinging at one end with said slid- 120 able carrier and a cam actuating said lever.

4. A machine for making wire nails and pins, having a stationary knife carrier and a slidable knife carrier, knives in each of the carriers radiating from the axis of the 120 wire, a frame situated in front of both and having positive connection with the stationary carrier, a pair of head forming dies in said frame, one of said dies being slidable and the other stationary in said frame during 125 operation; a lever engaging with said movable die, a cam actuating said lever and a spring pressing said lever against said cam; a spring engaging with said slid- 130 able carrier and tending to draw the carrier outward

from the wire, a lever impinging at one end with said slidable carrier and a cam actuating said lever.

5. A machine for making wire nails and pins, having a stationary knife carrier and a slidable knife carrier, knives in each of the carriers radiating from the axis of the wire, a frame situated in front of both and having positive connection with the stationary carrier, a pair of head forming dies in said frame, one of said dies being slidable and the other stationary in said frame during operation; and means for reciprocating said movable die and said slidable carrier, and a feed device for intermittently moving the wire in the direction of the dies, said device comprising a wire-holder and a slide therefor, 45 said slide being actuated by cam action.
- 10 6. A machine for making wire nails and pins, having a stationary knife carrier and a slidable knife carrier, knives in each of the carriers radiating from the axis of the wire, a frame situated in front of both and having positive connection with the stationary carrier, a pair of head forming dies in said frame, one of said dies being slidable and the other stationary in said frame during 50 operation; and means for reciprocating said movable die and said slidable carrier.
- 15 7. A machine for making wire nails and pins, having a stationary knife carrier and a slidable knife carrier, knives in each of the carriers radiating from the axis of the wire, a frame situated in front of both and having positive connection with the stationary carrier, a pair of head forming dies in said frame, one of said dies being slidable and the other stationary in said frame during 55 operation; and means for reciprocating said movable die and said slidable carrier, and a feed device for intermittently moving the wire in the direction of the dies.

- 20 7. A machine for making wire nails and pins, having a stationary knife carrier and a slidable knife carrier, knives in each of the carriers radiating from the axis of the wire, a frame situated in front of both and having positive connection with the stationary carrier, a pair of head forming dies in said frame, one of said dies being slidable and the other stationary in said frame during 55 operation; and means for reciprocating said movable die and said slidable carrier, and a feed device for intermittently moving the wire in the direction of the dies.

25 pins, having a stationary knife carrier and a slidable knife carrier, knives in each of the carriers radiating from the axis of the wire, 35 a frame situated in front of both and having positive connection with the stationary carrier, a pair of head forming dies in said frame, one of said dies being slidable and the other stationary in said frame during 40 operation; and means for reciprocating said movable die and said slidable carrier, and a feed device for intermittently moving the wire in the direction of the dies, said device comprising a wire-holder and a slide therefor, 45 said slide being actuated by cam action.

30 8. A machine for making wire nails and pins, having a stationary knife carrier and a slidable knife carrier, knives in each of the carriers radiating from the axis of the wire, 50 a frame situated in front of both and having positive connection with the stationary carrier, a pair of head forming dies in said frame, one of said dies being slidable and the other stationary in said frame during 55 operation; a spring tending to withdraw said head punching die from said frame, and a lever engaging said punching die, and a cam for oscillating said lever.
